United States Patent Office

Des. 181,714
Patented Dec. 17, 1957

181,714

DECANTER

Ernest L. Du Pree, Weston, Conn., and James Rosati,
New York, N. Y., assignors to Schenley Industries,
Inc., New York, N. Y., a corporation of Delaware

Application October 31, 1956, Serial No. 43,615

Term of patent 14 years

(Cl. D58—8)

Figure 4 is a fragmentary side elevational view of the upper neck portion of the decanter with the cap removed, and

We claim:

The ornamental design for a decanter, as shown.
